FIG. 1 is a side elevation of a camper boat embodying my new design;

FIG. 2 is a top plan view of the boat;

FIG. 3 is a front elevation of the boat;

FIG. 4 is a rear elevation of the boat; and

FIG. 5 is a perspective view of the boat.

In FIGS. 1, 3 and 4 there is a broken line disclosure of a camper which the boat of my design may carry, but the design thereof is no part of the present invention.
